UNITED STATES PATENT OFFICE

HARRY L. FINKELSTEIN, OF NEW YORK, N. Y., ASSIGNOR TO MANHATTAN TERRAZZO
BRASS STRIP CO. INC., OF NEW YORK, N. Y.

STRIP-FORMING MACHINE

Application filed December 23, 1925. Serial No. 77,418.

This invention relates to a strip-forming machine, and has for its object to provide a semi-automatic machine for forming twin anchor brass dividing strips for terrazzo and other plastic work.

5 A further object is the provision of a machine that will form such strips expeditiously and economically. Other objects will become apparent as the description proceeds.

10 While I have disclosed a preferred embodiment of the machine for purposes of illustration, it should be understood that the structure may be modified in various ways without departure from the true spirit and 15 scope of the invention as hereinafter defined and claimed.

In the drawings:—

Fig. 1 is a plan view of the machine.

20 Fig. 2 is an end elevation looking from the right in Fig. 1.

Fig. 3 is an enlarged detail of some of the parts shown in Fig. 1.

Fig. 4 is a section on line 4—4 of Fig. 1.

Fig. 5 is a section on line 5—5 of Fig. 1.

25 Fig. 6 is a section on line 6—6 of Fig. 1.

Fig. 7 is a section on line 7—7 of Fig. 1.

Fig. 8 is a section on line 8—8 of Fig. 7.

Fig. 9 is a section on line 9—9 of Fig. 7.

Fig. 10 is a section on line 10—10 of Fig. 7.

30 Fig. 11 is a detail of the cam means used to operate the clamping jaws.

Fig. 12 is a section on line 12—12 of Fig. 1.

Fig. 13 is a section on line 13—13 of Fig. 14.

35 Fig. 14 is a detail of the strip-supporting means.

Fig. 15 is a perspective view of a completed strip.

Fig. 16 is a side elevation of a modified strip.

40 Fig. 17 is a section on line 17—17 of Fig. 16.

Referring more particularly to the drawings, the legs 20, 21 and 22 carry cross arms 23, 24 and 25, upon which the main parts of the machine are carried. Longitudinal supports 26, 27, 28 and 29 are secured on arms 24 and 25 in spaced relation to each other. Short brace members 30 and 31 are secured to supports 26 and 27, while brace members 32 and 33 are secured to supports 28 and 29. A rotary shaft 34 is mounted in bearings

35 on supports 23, 24, 30, 31 and 25. A second shaft 36 is mounted in bearings 35 on supports 23, 24, 32, 33 and 25. The shafts are driven through intermeshing gears 37 and 38 keyed to shafts 34 and 36 respectively. A sprocket 44 is idly mounted on shaft 34 and is adapted to rotate said shaft through clutch mechanism 45. The sprocket 44 is driven through a chain 40 from sprocket 39 mounted on shaft 41, the latter shaft 55 being rotated by a driven pulley 42. An idler sprocket 44' is mounted on shaft 43 to keep the chain under proper tension.

The blank strip 46 is gripped between two movable jaws 47 and 48, which are normally held apart by springs 49 mounted over rods 50 slideable in sockets 51 secured to the jaws (Fig. 4). Jaw 47 is guided in its lateral movement by guide rods 52 secured to the jaw and slideable through the supports 26 and 27. Jaw 48 is guided by similar guide rods slideable through supports 28 and 29. Guide blocks 53 (Fig. 3) are mounted in the jaws and press firmly against the sides of the strip.

75 The jaws are pressed together by cams 54 which are mounted on supports 27 and 28 and are operated through rotation of gears 57 by racks 55 carried on rack bars 56, the bars being reciprocated by cams 58 and 59 keyed to shafts 34 and 36 respectively. Similar cam grooves 60 are formed in cams 58 and 59. A sleeve 61 (Fig. 11), slideably keyed on each rack bar 56, carries a roller 62 riding in cam groove 60. An expansion spring 63, stiffer than springs 49, normally holds the sleeve 61 in extended position.

When the machine is operated from the position shown in Fig. 1, the cam 59 will be rotated in a contraclockwise direction. The cam groove is so formed that during the first part of the rotation the rack bar will remain in the position shown, and the jaws will remain closed for the work period. During the next part of the rotation the bar is moved 90 quickly toward the right, releasing cams 54, and allowing springs 49 to fully open the jaws. The formed strip drops through the jaws to the delivery slides 110, and the bar is then moved toward the left, partially clos- 95

ing the jaws. The machine then automatically stops for the insertion of a second blank strip, and upon starting the machine again the bar is moved farther to the left, closing the jaws upon the second blank.

5 Should the jaws close firmly before the roller 62 has reached the extreme limit of its movement to the left, the spring 63 will yield, preventing any strain on the mechanism.

10 The jaws 47 and 48 must separate a sufficient distance to allow a finished strip 64 having oppositely extending ears 65 to pass between them. Such a wide separation of the jaws would allow a newly inserted blank to fall on its side instead of standing upright.

15 Supplemental jaws 66 (Fig. 3) are therefore provided which will have a smaller clearance when opened and which will clamp the strip between the points at which ears 65 are formed. These supplemental jaws are carried on posts 67, which are slideable in the main jaws and are mounted on supports 27 and 28 for limited movement. Each post 67 has a reduced extension 68 which slides in 25 a corresponding opening formed in the support member. A spring 70 surrounds the extension 68 in a countersink 69 formed in the support member, said spring pressing against a stop 71 on the extension and tending normally to hold the shoulder 72 on post 67 against the support member. It will be evident that when the main jaws 47 and 48 are moved together by the cams 54 they will carry with them the supplemental jaws 35 66. When jaws 47 and 48 are allowed to separate, jaws 66 will separate under influence of springs 70 until the shoulders 72 contact with the support members. This will allow only a limited separation between the supplemental jaw members, while the main jaw members will continue to separate as far as the members supporting cams 54 will permit. Guides 73 are provided to facilitate the insertion of the blank strips between the jaws.

40 45 The lower edge of the blank strip is normally supported on studs 74 secured to jaw 47 (Figs. 6, 12 and 13). In some instances it is desired to use the machine to form strips that are narrower than the one illustrated, and which must be supported in a higher position in the machine. For this purpose spring-pressed pins 75 are mounted vertically in studs 74 and are adapted to be raised by cams 76 formed on rod 77 when the latter is 50 moved to the left in Fig. 12. The strip will then rest on the upper ends of pins 75. The rod 77 is guided in members 78 secured to jaw 47.

While the strip is held between the jaws, 60 the ears 65 are punched by the tools 79 (Figs. 3 and 5), which are mounted in offset pairs on opposite sides of the strip as clearly shown in Fig. 3. The inner ends of the tools are guided in blocks 53 by side wear-plates 80 and 65 top plates 81. The outer ends of the tools

are held in the movable cross-heads 82 by set screws 83, and are adjustable longitudinally to take up wear by movement of screws 84. The cross-heads are moved inwardly by cams 85 pushing against hardened steel blocks 86 mounted on the cross-heads, and are pulled outwardly by pins 87 carried by the cross-heads moving in tracks 88 in the cams.

70 The operation of the machine is controlled by the clutch 45 now to be described. The sprocket 44, which is idly mounted on shaft 34, is continuously rotated. Clutch member 89 is keyed to shaft 34 and carries the clutch dog 90, which is adapted to extend into a slot 91 formed in the face of sprocket 44 to cause member 89 to rotate with the sprocket. The dog has a shank 92 which is surrounded by a spring 93 normally pressing the dog toward the slot 91. The member 89 is provided with a groove 94 into which a control rod 95 extends. The control rod is mounted in a guide 96 and is normally projected into the groove 94 by a spring 97. The control rod carries a cam face 98 which cooperates with a cam face 99 formed on the dog to retract the latter from the slot 91.

75 A head 100 formed on the lower end of the control arm contacts with the framework to limit the upward movement of the arm, said head having a hook 101 formed thereon. A rod 102 is mounted to reciprocate in the framework and is guided by a pin 103 moving in a slot 104 formed in the framework. A hook member 105, formed to complement the hook 101, is pivoted on pin 103 and carries a cam surface 106 for cooperation with pin 107 mounted on the framework. The rod carries an offset extension 108 upon which bears the spring 109 normally holding hooks 101 and 105 in contact. Rod 102 is reciprocated by depressing the pedal 110 against the action of spring 111.

80 The operation of the machine is as follows:

85 When the pedal is depressed the rod 102 is moved downward, carrying with it the control rod 95. This action allows dog 90 to engage in slot 91, and hence causes member 89 and shaft 34 to rotate with sprocket 44. As rod 102 continues its downward movement 90 the cam surface 106 engages pin 107, moving hook 105 out of engagement with hook 101 and allowing the control rod 95 to be again projected into groove 94 by spring 97. Hence as member 89 rotates the cam surface 99 formed on dog 90 will ride up cam surface 98 formed on the control rod, whereby the dog will be retracted from slot 91 and shaft 34 will come to rest after one complete rotation with the parts again in the position shown in Fig. 7. After the foot pedal is released the spring 101 raises the pedal and rod 102 so that hooks 101 and 105 again become engaged, and the clutch mechanism is ready for another cycle of operation.

As shaft 34 moves, both cams 58 and 59 rotate, controlling the operation of the clamping jaws through mechanism set forth above. During the first part of their rotation the jaws close upon the blank, and while it is rigidly clamped, the cams 85 move the tools 79 to punch out the ears 65. All of the tools are not moved simultaneously, but they are divided into groups and operated in sequence to distribute the strain. The jaws then open widely, allowing the formed strip to drop through the jaws to the delivery slide 112, and then close to the point where the main jaws start to move the supplementary jaws. At this point the machine comes to rest and is ready to receive another blank strip.

By using square tools 79, square ears 65 will be formed as shown in Fig. 15, or by using triangular tools the machine will form triangular ears as shown in Figs. 16 and 17.

What I claim is:

1. In a strip forming machine, means for gripping a strip, means for punching ears to project in opposite directions from said strip while it is gripped, means for releasing said strip, and a control means upon a single actuation of which all of said means are operated.

2. In a strip forming machine, means for gripping a strip, means for punching ears to project in opposite directions from said strip while it is gripped, means for releasing said strip, a control means upon a single actuation of which all of said means are operated, and means for automatically stopping said machine after each of said means has been operated once.

3. In a strip forming machine, cam actuated means for gripping a strip, cam actuated means for punching an ear from said strip while it is gripped, cam actuated means for releasing said strip, and a control means upon a single actuation of which all of said means are operated.

4. In a strip forming machine, cam actuated means for gripping a strip, cam actuated means for punching an ear from said strip while it is gripped, cam actuated means for releasing said strip, a control means upon a single actuation of which all of said means are operated, and means for automatically stopping said machine after each of said means has operated once.

5. In a strip forming machine, means for gripping a strip, means located on each side of said strip for punching an ear from said strip, means for releasing said strip, and a control means upon a single actuation of which all of said means are operated.

6. In a strip forming machine, means for gripping a strip, means located on each side of said strip for punching an ear from said strip, means for releasing said strip, a control means upon a single actuation of which all of said means are operated, and means for auto-

matically stopping said machine after each of said means has operated once.

7. In a strip forming machine, primary jaws for gripping a strip, supplemental gripping jaws actuated by movement of said primary jaws, means for opening and closing said primary jaws, and means for punching an ear from said strip while it is held between the jaws.

8. In a strip forming machine, jaws for gripping a strip, cam means for closing and opening said jaws, tools located on each side of said strip for punching an ear from said strip, cam means for operating said tools, a control means, and operating means for causing one complete rotation of each of said cam means upon a single actuation of said control means.

9. In a machine of the kind described, spaced pairs of gripping jaws movable toward and from each other, cams pressing against said jaws to force the jaws of each pair towards each other, and means for simultaneously actuating all of said cams.

10. In a machine of the kind described, spaced pairs of gripping jaws movable toward and from each other, rotatable cams pressing against said jaws to force the jaws of each pair towards each other, gears associated each with a respective cam to rotate said cam, rack bars each meshing with all of the gears on a respective side of said jaws, and means for simultaneously reciprocating said rack bars.

11. In a machine of the kind described, spaced pairs of gripping jaws movable toward and from each other, rotatable cams pressing against said jaws to force the jaws of each pair towards each other, gears associated each with a respective cam to rotate said cam, rack bars each meshing with all of the gears on a respective side of said jaws, a pair of shafts, gears connecting said shafts for rotating the shafts in unison, and a cam on each shaft having operative connection with the rack bars to reciprocate the same.

12. In a machine of the kind described, spaced pairs of gripping jaws movable toward and from each other, cams pressing against said jaws to force the jaws of each pair towards each other, means for simultaneously actuating all of said cams, spaced pairs of punching and bending members arranged to move at right angles to the jaws, each pair being arranged with its members on opposite sides of the series of jaws and operable oppositely to each other, and means for simultaneously actuating said punching and bending members in timed relation to the closing of said jaws.

13. In a machine of the kind described, spaced pairs of gripping jaws movable toward and from each other, rotatable cams pressing against said jaws to force the jaws

of each pair towards each other, gears associated each with a respective cam to rotate said cam, rack bars each meshing with all of the gears on a respective side of said jaws, means for simultaneously reciprocating said rack bars, spaced pairs of punching and bending members arranged to move at right angles to the jaws, each pair being arranged with its members on opposite sides of the series of jaws and operable oppositely to each other, and means for simultaneously actuating said punching and bending members in timed relation to the closing of said jaws.

14. In a machine of the kind described, spaced pairs of gripping jaws movable toward and from each other, rotatable cams pressing against said jaws to force the jaws of each pair towards each other, gears associated each with a respective cam to rotate said cam, rack bars each meshing with all of the gears on a respective side of said jaws, a pair of shafts, gears connecting said shafts for rotating the shafts in unison, a cam on each shaft having operative connection with the rack bars to reciprocate the same, spaced pairs of punching and bending members arranged to move at right angles to the jaws, each pair being arranged with its members on opposite sides of the series of jaws and operable oppositely to each other, and means for simultaneously actuating said punching and bending members in timed relation to the closing of said jaws.

15. In a machine of the kind described, spaced pairs of gripping jaws movable toward and from each other, rotatable cams pressing against said jaws to force the jaws of each pair towards each other, gears associated each with a respective cam to rotate said cam, rack bars each meshing with all of the gears on a respective side of said jaws, a pair of shafts, gears connecting said shafts for rotating the shafts in unison, a cam on each shaft having operative connection with the rock bars to reciprocate the same, spaced pairs of punching and bending members arranged to move at right angles to the jaws, each pair being arranged with its members on opposite sides of the series of jaws and operable oppositely to each other, and means for simultaneously actuating said punching and bending members in timed relation to the closing of said jaws, said last means including cams fixed on said shafts and engaging said punching and bending members.

In testimony whereof I affix my signature.
HARRY L. FINKELSTEIN.
